[57] CLAIM

The ornamental design for a flag holder, as shown.

DESCRIPTION

FIG. 1 is a perspective view of the flag holder of the present invention.

FIG. 2 is a front elevational view of the flag holder.

FIG. 3 is a side elevational view of one side of the flag holder.

FIG. 4 is a rear elevational view of the flag holder.

FIG. 5 is a side elevational view of the other side of the flag holder.

FIG. 6 is a top plan view of the flag holder; and,

FIG. 7 is a bottom plan view of the flag holder.

The broken line showing is for illustrative purposes only and forms no part of the claimed design.
